CLAIM

The ornamental design for an underwater pool cleaning apparatus, as shown and described.

DESCRIPTION

FIG. 1 is a perspective view of an underwater pool cleaning apparatus showing my new design;

FIG. 2 is a top plan view thereof;

FIG. 3 is a left side elevational view, the right side being identical in appearance thereof;

FIG. 4 is a front elevational view thereof;

FIG. 5 is a rear elevational view thereof; and,

FIG. 6 is a bottom plan view thereof.

The broken line showing of a suction base is for illustrative purposes only and forms no part of the claimed design.

FIG. 1.**FIG. 2.****FIG. 3.**

FIG. 4.

FIG. 5.

FIG. 6.

UNITED STATES PATENT AND TRADEMARK OFFICE

CERTIFICATE OF CORRECTION

PATENT NO. : Des. 304,505

DATED : November 7, 1989

INVENTOR(S) : Robert W. Maier, Charles J. Patterson, Deiter Rief,
John Gard and Herman E. Frentzel

It is certified that error appears in the above - identified patent and that said Letters Patent is hereby corrected as shown below:

In the Description:

In the description, after the word suction please
replace "base" with --hose--.
